UNITED STATES PATENT OFFICE

CHARLES W. MABEY, OF INDIANAPOLIS, INDIANA

DESIGN FOR A PEANUT DISPENSER

Application filed July 17, 1931. Serial No. 40,580. Term of patent 7 years.

To all whom it may concern:

Be it known that I, CHARLES W. MABEY, a citizen of the United States, residing at Indianapolis, in the county of Marion and State of Indiana, have invented a new, original, and ornamental Design for Peanut Dispensers, of which the following is a specification.

Reference is had to the accompanying drawings, in which

Fig. 1 is a front view in perspective of a peanut dispenser, showing my new design, and

Fig. 2, a top plan view of the dispenser.

I claim:

The ornamental design for a peanut dispenser, as shown.

In testimony whereof I affix my signature.

CHARLES W. MABEY.
